FOUR LAYER DIODE TRANSMISSION GATE
Richard L. Given, El Paso, Tex., Richard G. Nyder, Glenview, Ill., and Richard C. Lee, Allston, Mass., assignors, by mesne assignments, to the United States of America as represented by the Secretary of the Navy

Filed July 23, 1959, Ser. No. 829,164
5 Claims. (Cl. 307—88.5)

This invention relates generally to gating circuits and more particularly to sample and hold gates.

In a sample and hold gate, the output voltage assumes a steady value during the enable interval. This value is held during the disable interval, until the arrival of a next enabling pulse, at which time the output voltage assumes a new value, corresponding to the new value of the input voltage. The storage device most commonly employed in such a circuit is a capacitor. The requirements of the sample and hold gate then is such that the impedance seen by the capacitor in the disable state is extremely high to prevent any appreciable discharge of the capacitor during the hold portion of the cycle. It is also necessary that the transmission impedance in the enabled state be sufficiently low so that the capacitor may be charged to the output voltage in as short a time as possible. With regard to these specific requirements, the prior art is greatly lacking.

In the sample and hold gate circuit which has been invented, four-layer diodes are utilized. The four-layer diode volt-ampere characteristics are such that a negative resistance region is bounded by two stable states: a high conductance region and a high impedance region, which according to published characteristics corresponds to impedances of ten to thirty ohms and ten to 100 megohms respectively.

A principle object of the instant invention is to provide a high speed high performance sample and hold gate.

Another object of the instant invention is to provide a gate circuit having extremely low impedance during an enabled period and extremely high impedance during a disabled period.

Still another object of the instant invention is to provide a sample and hold gate utilizing four-layer diodes.

Still another object of the instant invention is to provide an inexpensive high performance sample and hold gate circuit.

Other objects and many of the attendant advantages of this invention will be readily appreciated as the same becomes better understood by reference to the following detailed description when considered in connection with the accompanying drawings wherein:

The figure depicts the preferred schematical arrangement of the instant invention.

Referring to the figure, the sample and hold gate is shown. A pulse transformer **10** having a primary **12** and a secondary **14** is utilized in this preferred form of the invention. The transformer secondary **14** is, in this form of the invention, connected to the cathode **16** of a four-layer diode **18**. The plate **20** of diode **18** is then coupled to the plate **22** of a second four-layer diode **24**. The cathode **26** of four-layer diode **24** is coupled through the resistor **28** to the other end of the pulse transformer secondary **14**. A series input resistor **30** is coupled to the plate of diode **24** and cathode of diode **18** and also to an input connection **32**. In this form of the

2

invention a storage device is utilized and is a capacitor **34**. This capacitor **34** is connected to the cathode **26** of four-layer diode **24**. An output connection is also coupled to the junction of capacitor **34** and diode cathode **26**.

5 In operation, the invention functions as follows: When a negative going pulse is applied to terminal **38** of the transformer primary **12**, the diodes **18** and **24** are converted from a high to a low impedance condition if the voltage appearing across the secondary **14** of the pulse transformer exceeds their breakdown voltage. With the diodes in the conducting state, a potential appearing at the input terminal **32** will be gated onto the capacitor **34** regardless of whether this change involves either charging or discharging the capacitor. After the voltage on the 10 capacitor has settled out to a steady-state value, the removal of the negative potential from terminal **38** renders both diodes **18** and **24** non-conductive, since the current through them falls below the minimum value necessary to hold them in the conducting states. This is to say, 15 each of the diodes reverts to a high impedance condition. With the diodes in this state, the capacitor **34** is prevented from discharging back through the gate circuit and into the input source, consequently the voltage placed on the capacitor during the enabled period is retained during 20 the disabled period.

What is claimed is:

1. A gate circuit comprising a transformer having a primary input winding and also having a secondary output winding, a first diode means and a second diode 30 means, each of said first and second diode means having plate and cathode elements, the plate element of said first diode means being directly connected to the cathode element of said second diode means and each of said other diode elements being connected to an opposing end of 35 said secondary output winding of said transformer, variable signal input means coupled to the plate element of said first diode means and signal output means directly coupled to the cathode element of said first diode means, wherein each of said diodes is a four-layer diode.
2. The structure of claim 1 wherein said transformer 40 is a pulse transformer.
3. The structure of claim 2 including storage means coupled to said output means.
4. The structure of claim 3 wherein said storage means 45 is a capacitor.
5. A sample and hold circuit comprising input means for inserting input voltages into the circuit, output means for holding the sample input voltages, a diode gate means coupled in series between the input and output means 50 which when enabled provides a low impedance path between said input and output means and when disabled provides a high impedance path between said input and output means, a diode switching means coupled in series with said diode gating means to enable and disable said 55 diode gating means whereby the diode may be disabled to permit the input voltages to be stored in the output means and may be disabled to prevent leakage of the stored voltage, said output means including a capacitor in series with said diode gating means and said input means, said diode gating means being a four-layer diode and said diode switching means being a four-layer diode, a pulse 60 transformer and resistor in series with said first mentioned four-layer diodes, said input means including a resistor coupled in series with said four-layer diodes.
